DOOR OPERATING MECHANISM

Aaron Brodsky, New York, N. Y.

Application October 12, 1932, Serial No. 637,418

12 Claims. (Cl. 189—7)

The present invention relates broadly to door operating mechanisms and more especially to an operating mechanism for a sliding door of the type commonly used in penal institutions.

5 The present invention comprises automatic mechanisms whereby a plurality of doors, as for example, cell doors may be unlocked, opened, and closed by remote control apparatus.

10 The invention also contemplates manually operated mechanisms whereby a plurality of cell doors may be simultaneously unlocked and then individually manually opened and closed should the automatic mechanism become disabled.

15 A further feature of the invention contemplates an automatic mechanism as specified for unlocking, opening, and closing a group of doors and provision for manually unlocking, opening, and closing individual doors of the group should the automatic mechanism become disabled.

20 More specifically, the present invention comprises electrically operated mechanism for unlocking and opening and closing the doors with the mechanisms constructed in such manner that the electric motors may be started under a very light load which is sufficient to unlock the doors and then after the motors have been running at full speed, the heavy load of opening the doors is applied to the motor. On the closing movement of the door, the motors operate at full speed for a period of time with substantially no load and then the load comprising the inertia of the door is picked up and carried along until the door is closed by the operation of the motor. These features are particularly desirable since it 25

30 enables the utilization of small motors to do the work which would ordinarily require large motors providing the full operating load had to be carried as soon as the motors started.

35 Other features of the invention will be apparent

40 to those skilled in the art and will in part be

45 pointed out hereinafter in the specification by reference to the drawings which comprises a disclosure of the preferred form of the invention.

45 It is realized that the invention may be carried out in structures other than those specifically disclosed herewith, and, therefore, the present disclosure is to be understood as illustrative and not in the limiting sense.

50 Fig. 1 illustrates more or less diagrammatically an elevation of the preferred form of the invention as applied to a single door.

55 Fig. 2 illustrates a section of the device shown in Fig. 1 taken on line 2—2 of Fig. 1.

55 Fig. 3 is a detail front elevation of a portion of the operating mechanism shown in Fig. 2.

Fig. 4 is a detail elevational view on line 4—4 of Fig. 1, showing the parts in section, of the manually operable mechanism for releasing the locks on the cell doors.

60 Fig. 5 is a plan view of a portion of the mecha-

nism illustrated in Fig. 4 on a section taken on line 5—5 of Fig. 4.

Fig. 6 is a detail view illustrating the operating locking bar for the cell door.

Fig. 7 illustrates a detail of the locking device for the cabinets enclosing the mechanism.

Fig. 8 illustrates a plurality of cell doors showing manually operated levers for manually unlocking the cell doors and disabling the automatic opening and closing mechanism and also the manually operating device for unlocking the cabinet doors of the operating mechanism.

Referring to the drawings and more especially to Fig. 1, a drive screw shaft 1 is mounted for rotation in the frame members 2 and 4 above the cell door 5 and carries a large gear 6 which engages a pinion 7 on the drive shaft of an electric motor 8.

The cell door 5 is suspended from trackways 9 and 10 by means of anti-friction wheels 11 and 11 secured to the cell door, so that the door has a sliding movement in opening and closing.

The drive screw shaft 1 carries a screw threaded block 12 which is prevented from rotating by a square shaft 14 that extends through an interlock member 15 which has trunnions mounted for rotation in the bearings 16 formed in the lower part of the screw threaded block 12. Preferably, in order to facilitate assembly, the screw threaded block 12 is made in two pieces which are secured together by bolts 17. The interlock member 15 is provided with a laterally extending arm 18 adapted to normally rest on an interlock block 19 secured to the top of the cell door 5. This block 19 has a slideway 20 in the upper end thereof, the length of which slideway is longer than the width of the arm 18, so that the arm 18 has an idle movement before engaging the ends of the slideway 20. The top of the screw threaded block 12 is provided with a short cam 21 which engages a wedge cam 22 on a lever 24 which is pivoted to the mechanism frame members 25 and 26. The lever 24 is connected at its outer end with the locking bar 27 for the cell doors. This locking bar 27 is mounted in guideways 28 (Fig. 6) and is provided at intervals with openings 29 to receive the locking heads 30 integral with the front edge of the cell door 5 so that when the cell doors are closed, the weight of the locking bar drops the bar between the nose 31 on the locking head 30 to lock the cell door closed. This mechanism is mounted in the framework of the door in such manner as to be inaccessible from the inside of the cell.

In the operation of a single unit with the parts in position shown in Fig. 1, the operator throws a switch 32 (Fig. 8) which energizes the electric motor 8 to turn the drive screw shaft 1 in such direction as to move the screw block 12 toward the right of Fig. 1. The first operation of this

movement is to slide the short cam 21 beneath the wedge cam 22. At approximately the time when the tips of these two cams are in contact, the arm 18 of the interlock engages the right end of the 5 interlock block 19 and the full load now comes on the motor 8. In other words, the door begins to slide toward the right. The contact of the high points of the cams 21 and 22 has lifted the locking bar 27 in such manner that the bar clears the nose 31 of the locking heads 30. As the motor 10 continues to run and the door starts to open, the short cam 21 gradually slides beneath the long face of the wedge cam 22, thereby slowly dropping the locking bar 27. In the meantime, the 15 nose 31 of the locking head 30 has passed sufficiently beyond the sides of the opening 29 in the locking bar so that the door is free to move in a sliding motion which carries the door to open position. From the foregoing, it will appear that 20 the opening movement of the door is one continuous cycle. This cycle begins with the energizing of the motor 8 which continuously rotates the drive screw shaft 1 until the cycle is completed. In the initial portion of this single cycle, 25 the screw threaded block 12 moves to slide the short cam 21 beneath wedge shape cam 22 to raise the lever 24 and thus lift the locking bar 27 to unlock the cell doors 5. As this cycle of movement continues, the arm 18 contacts with the 30 interlock block 19 and the opening movement of the door begins and continues until the door is finally completely open. The electric motors 8 are so constructed that if the operator does not 35 open the switch 32 promptly when the cell door has been fully opened, the motor stalls without serious damage. In other words, the motor is constructed to carry very severe overload. The motor is also reversible so that by reversing the 40 position of the switch 32, the electrical current is reversed and the motor is caused to rotate in the opposite direction. When the current in the motor is reversed, the screw shaft 1 is rotated in the direction to move the screw block 12 to the left in Fig. 1. Since the arm 18 has been in engagement with the right end of the slideway 20, 45 the reversal movement of the motor causes the block to slide idly while the motor is started and after a short interval, the arm 18 engages the left end of the slideway 20 thereby initiating the closing movement of the door. As the door continues to close, the cam 21 rides upon the long wedge cam 22, and thereby lifts the locking bar 27 to raise the same above the nose 31 of the locking 50 head 30 until the flat part 34 of the nose 31 is beneath the locking bar. As the locking bar is released by the cam 21 sliding from beneath the cam 22, the bar 27 rests on the flat part 34 of the nose 31 while the door is making the final closing movement. When the door is 55 finally closed, the locking bar 27 drops into position behind the nose 31 and the cell door is securely locked closed. Here again, the switch 32 is permitted to stay closed until all of the doors in the series are securely locked and closed. When 60 the doors are closed the motor 8 stops because the screw block 12 cannot be moved further due to the door being closed. However, as above explained, the motor is designed to take this over-load without danger of burning out.

70 Provision is made to manually release either a series of doors or a single door in case the automatic electrically driven mechanism should fail to function. The manual release comprises a square bar 35 slidably movable across the entire 75 series of cell doors as illustrated in Fig. 8. This

shaft is connected with a hand lever 36 having a latch 37 normally locked in a notch in the segment 38. By releasing the latch 37 in the notch in the segment and pulling the hand lever 36 outwardly, the square bar 35 is moved lengthwise. This bar carries an actuator 39 for each cell door equipment. This actuator is connected by a sliding pin-slot 40 with one arm of a bell crank 41 mounted on the frame member 2 and connected at its other arm with a thrust link 42. The thrust link is provided with a long slot 44 in which is mounted a pin 45 on an arm 46 mounted on the square shaft 14. Another arm 47 also mounted on the shaft 14 extends laterally therefrom and is connected by an adjustable link 48 with a cam 15 arm 49 pivoted on the mechanism frame member 26. This cam arm 49 extends beneath the lever 24 which is connected with a locking bar 27.

It will be observed that the endwise movement of the square bar 35 in the direction of the arrow 20 Fig. 5, will operate to rotate the square shaft 14 in the direction of the arrow in Fig. 4. This rotation of the square shaft 14 through the link 48 on the cam arm 49 raises the lever 24 and the locking bar 27 to unlock the cell doors 5. 25 This movement of the square shaft 14 also turns the interlock member 15 on its trunnions and lifts the arm 18 above the slideway 20 in the interlock block 19. The cell door is now both unlocked and freed from the automatic operating 30 mechanism so that the cell door may be opened manually. This square bar 35 and connected parts operates to release an entire row of cell doors, as may be necessary in cases of emergency.

The mechanism for automatically operating 35 each cell door is all mounted within a cabinet as illustrated in Fig. 2. This cabinet is provided on the front face with a cabinet door 50 which is locked in place by the lock rod 51 extending past all of the cell doors of a tier of cells. This 40 lock rod 51 carries latches 52 as illustrated in Fig. 7, which engage rivet heads 53 as shown in Fig. 2. The upper edges of the cabinet doors are provided with rivet heads 54 which fit in bayonet openings 55 in the frame member 2 45 (Figs. 1 and 2) so that when the rivet head 54 has passed through the round portion of the opening 55, the door 50 drops downward and the upper part of the door is secured to the frame. The lower part of the door 50 is provided with 50 a lug 56 that drops over the frame member 4. It will be observed that by operating the hand lever 57 to release the latch 58 thereof from the notch in the segment 59 and then sliding the lock rod 51, the lock 52 releases the rivet head 55 53 so that the cabinet door 50 may be removed. When this is done, the lever arm 60 may be reached through the opening left by removal of the cabinet door 50. This lever may be provided with a notch 61 in which the push bar 60 62 (illustrated in dotted lines Fig. 4), may be inserted, whereby an upward thrust on this bar 62 rotates the square shaft 14. The thrust pin 45 on the arm 46 travels idly in the long slot 44 and the arm 47 through the adjustable link 65 48 operates the cam arm 49 to lift the lever 24 and the locking bar 27, thereby unlocking an individual cell. The rotation of the shaft 14 as has previously been explained raises the lateral arm 18 from the slideway 20 so that the door 70 is released for manual opening operation.

It is to be understood that the switch 32 and the operating levers 36 and 57 are located within a locked room which is not available to the inmates of the cells. It is also to be understood 75

that all of the operating mechanism for the cell doors is securely mounted in cabinets above the cell door which are thoroughly protected against access from anyone within the cell.

5 The present invention provides automatic means whereby large groups of cells may be controlled by remote control. Also, large groups of cells may be controlled by manual remote control, and in case of necessity individual cells may 10 be rendered manually individually operative.

Having described my invention, I claim:

1. A door operating mechanism comprising in combination a door, locking means for said door, a main control shaft, a remote controlled motor 15 to operate said main control shaft, means operated by the initial portion of one cycle movement of said shaft to unlock said locking means, and means operated by the continued portion of the same cycle movement of said shaft to open said 20 door.

2. A door operating mechanism comprising in combination a door, locking means for said door, a main control shaft, a remote controlled motor to operate said main control shaft continuously for one cycle of operations, means operated on the initial movement of said shaft to unlock said locking means, means operated on the continued movement of said shaft to open said door, and manually operated means to release 25 said door from said control shaft and to unlock said door.

3. A door operating mechanism comprising in combination a door, a locking bar operated by gravity to lock said door when closed, a main control shaft, an electric motor to operate said main control shaft, means operated by said shaft to raise said locking bar against gravity during the initial movement of said shaft, and a connection between said shaft and said door to open 30 said door and to permit an idle movement between the shaft and door during the raising of the locking bar to unlock the door.

4. A door operating mechanism comprising in combination a door, a locking bar operated by gravity to lock said door when closed, a main screw threaded control shaft, an electric motor 45 to operate said main control shaft, a nut mounted to travel on said shaft, a cam on said nut, a lever connected to said locking bar and operated by said cam to raise said locking bar against gravity during the initial movement of said shaft, and a connection between said shaft and said door to open said door and to permit an idle movement between the shaft and door during the raising of the locking bar to unlock the door.

5. A door operating mechanism comprising in combination a door, a main control screw shaft, an electric motor to rotate said control screw shaft, a threaded member mounted on said screw 50 shaft and adapted to move on said shaft when the same is rotated, means to prevent rotation of said threaded member, an interlock block carried by said door, interlock means carried by said threaded member and adapted to engage said interlock block on said door, and means to disengage said interlock means from said interlock block.

6. A door operating mechanism comprising in combination a door, a main control screw shaft, an electric motor to rotate said control screw 55 shaft, a threaded member mounted on said screw shaft and adapted to move on said shaft when the same is rotated, a cam operated by said member, a release shaft on which said member slides to prevent rotation of said member, an interlock 60 block carried by said door, interlock means car-

ried by said threaded member and adapted to engage said interlock block on said door, said interlock means being slidable on said release shaft and rotatable therewith, and means to rotate said release shaft to disengage said interlock 5 means from said interlock block.

7. A door operating mechanism comprising a door, a screw threaded main shaft, an electric motor to rotate said shaft, a threaded nut carried by said shaft and adapted to travel thereon 10 when said shaft is rotated, a square shaft, an interlock arm mounted in bearings carried by said threaded nut and slidable on said square shaft, an interlock block on said door and adapted to be engaged by said interlock arm, and 15 means to rotate said square shaft to disengage said interlock arm from said interlock block.

8. A door operating mechanism comprising a door, a lock for said door, a screw threaded main shaft, an electric motor to rotate said shaft, a 20 threaded nut carried by said shaft and adapted to travel thereon when said shaft is rotated, a square shaft, an interlock arm mounted in bearings carried by said threaded nut and slidable on said square shaft, an interlock block on said 25 door and adapted to be engaged by said interlock arm, an idle movement being provided between said arm and said block, means to unlock said lock during the initial idle movement between said arm and said block, and means to rotate 30 said square shaft to disengage said interlock arm from said interlock block.

9. A door operating mechanism comprising a door, a main control shaft, a motor to operate said shaft, a locking bar to lock said door when 35 closed, operating means connecting said shaft and said door whereby the operation of said shaft opens and closes said door, unlocking means actuated by said operating means to operate said locking bar to unlock said door, and means to 40 disable the effective operation of said operating means and said locking bar.

10. In a mechanism of the class described, a plurality of doors comprising a group, a lock for each door when closed, power means to simultaneously unlock all the doors of said group and to open and close the same, and separate means to unlock all the doors of said group and to release said doors from said power means whereby said doors may be manually opened and closed.

11. A mechanism of the class described comprising a group of doors, individual locking means for each door, individual power means for each door actuated from a single source of power whereby the whole group of doors may be simultaneously unlocked, opened and closed, and means independent of said power means to unlock all of the doors of said group and render all the individual power means ineffective to open and close said doors.

12. A mechanism of the class described comprising a group of doors, individual locking means for each door, individual power means for each door actuated from a single source of power whereby the whole group of doors may be simultaneously opened and closed, means to unlock all of the doors of said group and render all the individual power means ineffective to open and close said doors, a cabinet over each door enclosing the operating mechanism therefore, a locked cabinet door for each cabinet, and means to simultaneously unlock all the cabinet doors for a group of doors.
